REFRIGERATING MACHINE OF THE
ABSORPTION TYPEAlexander Bikkers, The Hague, Netherlands, as-
signor to Willem Frederik Poel, Haarlem,
NetherlandsApplication April 22, 1937, Serial No. 138,458
In the Netherlands April 29, 1936

5 Claims. (Cl. 62—119.5)

This invention relates to refrigerating machines of the absorption type in which the pressures are equalized by means of the addition of inert gas.

5 In applicant's Patent No. 2,020,763 it has been suggested to provide both the absorber and the evaporator with an individual circulatory pipe and to interconnect said pipes by a suitable conduit, through which refrigerant vapour from the 10 circulatory pipe of the evaporator diffuses into that of the absorber. This patented construction has the inconvenience that a certain amount of heat is necessarily transmitted from the absorber, through its circulatory pipe, to the second circulatory pipe and thence to the evaporator, whereby the efficiency of the machine is impaired. Moreover, diffusion is a very slow process, so that the 15 capacity of the machine under consideration is relatively small.

20 My present invention has for its object to meet the objections stated. With this object in view, I suggest to provide the absorber with a circulatory pipe, part of which is in direct contact with a wall portion of the evaporator and communicates therewith through a suitable opening, and to provide the evaporator with baffles along which the liquid refrigerant from the condenser is adapted to flow down so as to produce, within the evaporator, eddies whereby the refrigerant vapour is compelled to flow across said opening. Owing to the fact that a rich mixture of inert gas and refrigerant vapour is thus caused to continuously flow across the opening in the evaporator wall, said vapour is adapted to diffuse into the circulatory pipe of the absorber through a conduit, the length of which is practically nil, whereby a comparatively great amount of said vapour is conveyed per unit of time.

It will be appreciated that the wall portion, 40 which is common to the evaporator and the circulatory pipe of the absorber, may be very thin, since equal total pressures obtain on either side of said wall portion.

If the density of the refrigerant vapour, for instance ammonia, is smaller than that of the inert gas, for instance nitrogen, it is advisable to provide the aforesaid opening near the top of the evaporator, as under said circumstances the refrigerant has the natural tendency to rise. If, however, the inert gas is hydrogen, or helium, it is preferred for said opening to be located near the bottom of the evaporator.

In order that my invention may be well understood, reference is had to the annexed diagrammatic drawing, on which:

Fig. 1 is an elevation, partly in section of a refrigerating machine in accordance with the invention, and

Fig. 2 is an elevation, partly in section of a modified evaporator.

In Fig. 1, the numeral 2 designates the insulated wall of a cabinet, the interior space 4 of which is to be cooled.

Mounted outside said cabinet is a boiler or gas expelling vessel 3 provided with a heating device 10. This vessel is connected near its top with a liquid separator 5 having a plurality of baffles 6 and communicating, through a pipe 7, with the condenser 8, of which the lower and the upper portions are connected with the evaporator 12 15 through pipes 9 and 13, respectively.

The evaporator 12, which is mounted within the cabinet 2, is provided with two horizontal partitions 14, each having plain openings 16 and also openings 15 with upturned edges. The openings in the one partition are disposed in staggered relation to those in the other. Near the top, one of the side walls has an opening 17, through which the evaporator communicates with the descending section 22 of a circulatory 25 pipe 18, 19, 20, 21, 22, 23, 24, the section 18—19 of which acts as an absorber. At the junction between sections 24 and 18, said pipe opens into a vertical conduit 25, which has a horizontal extension 26 merging as at 27 into the boiler 3 and 30 is connected with the bottom portion of the evaporator 12 by a pipe 28.

Near its bottom, the boiler 3 is connected, through a conduit 29, with an auxiliary gas expeller 30 provided with a heating device 31 and 35 communicating at its top, through an ascending pipe 32, with a vessel 33 mounted inside the vapour space of the boiler 3. Said vessel 33 is connected near its bottom to a pipe 34 merging into section 19 of the circulatory pipe, and near its 40 top to a pipe 37a. The end of pipe 37a forms a nozzle opening into a mixing cone 38, which merges into a discharge cone 39 so as to form an injector, it being understood that said cones form parts of the circulatory section pipe 18. Pipe 34 45 is, through a substantial part of its length, enclosed by pipe 26, with which it forms a heat exchanger. Another heat exchanger is formed by sections 20 and 23 of the circulatory pipe.

Assuming the boiler 3 to be partly filled with 50 a strong aqueous solution of ammonia, the remaining space of the machine to be filled with compressed nitrogen, the modus operandi will be as follows.

Owing to the heat developed by the device 4, 55

refrigerant vapour (ammonia) is expelled from the strong solution in boiler 3, the refrigerant vapour being sent through the liquid separator 5 and pipe 7 to the condenser 8, wherein it is cooled and liquefied. The liquid refrigerant flows through pipe 9 onto the upper partition 14 of the evaporator 12, where it begins to evaporate. Part of the liquid refrigerant falls through the plain openings 16 of the upper partition onto the lower partition 14, through the plain openings 16 of which, part of the liquid may fall onto the bottom of the evaporator.

In the vicinity of openings 16 a very low temperature will be produced by sudden evaporation of the liquid refrigerant. Owing to the openings 15 having upturned edges, no liquid refrigerant can flow therethrough, so that the temperature near these openings will not so abruptly be reduced, the result being that eddies and vortexes are produced in the mixture of inert gas and refrigerant vapour, as indicated by the arrows. It will thus be understood that a rich gaseous mixture will continuously flow across the opening 17, so that the refrigerant vapour has ample of opportunity to diffuse into section 22 of the circulatory pipe, where it mixes with the poor gaseous mixture flowing therethrough in downward direction, so as to be conveyed to the absorber 18, 19.

Any liquid refrigerant collecting on the bottom of the evaporator is discharged through pipe 28 into conduit 25.

The heater 31 causes refrigerant vapour to be freed by the solution contained in the auxiliary boiler 30. Thereby, an emulsion of vapour and liquid is produced, and this emulsion rises through the narrow ascending pipe 32, whereby poor liquor is discharged into vessel 33.

From this vessel, the poor liquor flows through pipe 34, 35, 36 into the absorber section 19, whence it flows by gravity into section 18, where it absorbs the refrigerant vapour supplied thereto by sections 22, 23, 24. The rich liquor thus produced in the absorber is returned, through the conduit 25, 26, 27, to the boiler 3.

The refrigerant vapour collecting in the upper portion of vessel 33 is discharged into the absorber section 18 through the injector 37b, 38, 39, whereby the required circulation in the circulatory pipe is produced, it being understood that the pressure obtaining in vessel 33 is sufficiently in excess of that in the absorber in order that the injector may operate. This circulation causes the poor gaseous mixture coming from the absorber to flow through pipe 22 across opening 17, where it can take up refrigerant vapour from the evaporator and convey it to the absorber.

Since the hot section 20 of the circulatory pipe is in heat exchanging relation with the cold section 23, it is impossible for any appreciable amount of heat to be transmitted to the evaporator.

Pipe 13 equalizes the pressures obtaining in the condenser 8 and in the evaporator 12, respectively. This is necessary in order that the evaporator may be continuously supplied with liquid refrigerant and, consequently, the eddies required for conveying refrigerant vapour to the openings 17 may be produced without interruption.

Fig. 2 shows an alternative construction of the evaporator. The evaporator 12 here is provided with a plurality of sloping baffles 40 mounted

at different levels and in staggered relation with one another in such a manner that liquid refrigerant discharged by pipe 9 flows from the top portion of the upper baffle to the lower portion thereof, thence falls on the next baffle, and so on. Consequently, very low local temperatures will be produced in the vicinity of the lower edges of the baffles, owing to the sudden evaporation of liquid refrigerant, thus causing the required eddies to set up. In this alternative construction, the opening 17 is provided near the bottom of the evaporator, since this type of evaporator has been designed for a refrigerating machine in which hydrogen or helium is used as the inert gas.

What I claim is:

1. In a continuous absorption machine in which the pressures are equalized by means of the addition of inert gas, a gas expeller, a condenser, an evaporator and an absorber interconnected in series, a circulatory pipe on the absorber and partly contacting with a wall portion of the evaporator, an opening in said wall portion to establish communication between the evaporator and circulatory pipe, and baffle means provided in the evaporator, said baffle means being adapted to compel liquid refrigerant discharged from the condenser into the evaporator to flow towards the bottom of the evaporator in such a manner as to produce eddies in the gaseous mixture and cause refrigerant vapour continuously to flow across said opening.

2. In a continuous absorption machine containing an inert gas equalizing the differences in the refrigerant pressure, a gas expeller, a condenser, an evaporator and an absorber, a circulatory passage on the absorber partly contacting with a wall portion of the evaporator, an opening in said wall portion communicating with the said circulatory passage and baffle means provided in the evaporator, said baffle means being provided with apertures so formed that the liquid refrigerant discharged into the evaporator can fall through only some of said apertures, but is positively prevented from falling through others, in such a manner as to produce eddies in the gaseous mixture within the evaporator and cause mixture rich in refrigerant to flow across said opening.

3. In a continuous absorption machine containing an inert gas equalizing the differences in the refrigerant pressure, a gas expeller, a condenser, an evaporator and an absorber, a circulatory passage on the absorber partly contacting with a wall portion of the evaporator, an opening in said wall portion communicating with the said circulatory passage, and baffle means provided in the evaporator, said baffle means comprising a horizontal partition provided with an aperture having upturned edges, preventing the liquid refrigerant discharged into the evaporator from falling through the said aperture, and further provided with an aperture the edges of which are located at a lower level than those of the first mentioned aperture to permit the said liquid to fall down through it, the said apertures arranged in such a manner as to produce eddies in the gaseous mixture within the evaporator and cause mixture rich in refrigerant to flow across said opening.

4. In a continuous absorption machine containing an inert gas equalizing the differences in the refrigerant pressure, a gas expeller, a condenser, an evaporator and an absorber, a circulatory passage on the absorber partly contact-

ing with a wall portion of the evaporator, an opening in said wall portion communicating with the said circulatory passage and baffle means provided in the evaporator, said baffle means comprising a plurality of sloping baffle walls, each mounted so as to leave free a gas passage both at the higher and at the lower side of it.

5. In a continuous absorption machine containing an inert gas equalizing the differences in the refrigerant pressure, a gas expeller, a condenser, an evaporator and an absorber, a circulatory passage on the absorber partly contacting with a wall portion of the evaporator, an open-

ing in said wall portion communicating with the said circulatory passage, and baffle means provided in the evaporator, said baffle means being adapted to compel liquid refrigerant discharged from the condenser into the evaporator 5 to flow towards the bottom of the evaporator in such a manner as to produce eddies in the gaseous mixture and cause mixture rich in refrigerant continuously to flow across said opening, and means arranged for supporting circulation in the circulatory passage and operated by pressure generated outside the absorber and evaporator.

ALEXANDER BIKKERS.
